AUXILIARY WINDOW

Benjamin J. Blackmore, Cuyahoga Falls, Ohio

Application March 13, 1945, Serial No. 582,455

5 Claims. (Cl. 160—92)

1

This invention relates to an auxiliary window of the type in which panes of glass provide closure means supplemental to the standard window, and in which the panes are interchangeable with screens.

An object of the invention is to provide an auxiliary window of the type described adapted to be installed interiorly of the standard window, the same having improved means whereby glass and screen closure panels may be quickly and interchangeably mounted from the interior, in accordance with weather changes, and without creating a problem of storage of closure panels not necessarily required at a particular time.

Other objects of the invention will be manifest from the following brief description and the accompanying drawings:

Figure 1 is an interior elevational view, partly broken away, of an auxiliary window embodying the features of the invention, and mounted in a window frame.

Figure 2 is a vertical cross-section, taken substantially at the line 2—2 in Figure 1.

Figure 3 is a fragmentary cross-section, on an enlarged scale, taken substantially on the line 3—3 of Figure 1.

Figure 4 is a horizontal cross-section, partly broken away, taken substantially on line 4—4 of Figure 1.

Figure 5 is an enlarged fragmentary cross-section, taken on line 5—5 of Figure 1.

Figure 6 is a fragmentary cross-section, corresponding to the lower portion of Figure 3, and illustrating a modified form of the invention.

Referring to Figures 1 to 5 of the drawings, the numeral 10 designates a window frame of standard type having trimming strips 11, 11 inwardly of the usual double-sashed window (indicated in chain-dotted lines in Figure 2), which strips for the present purposes are utilized as a blind stop providing an interiorly presented blind seat 12. Hinged to one side of frame 10, as indicated at 13, 13, may be top and bottom sashes 14 and 15, respectively, of an auxiliary window adapted to be seated snugly within frame 10 against the blind seat 12, the sashes being swingable interiorly on the hinges 13.

The top sash 14 comprises stiles 16 and 17, top and bottom rails 18 and 19, and an intermediate rail 20, defining vertically spaced openings 21 and 22. Similarly, on bottom sash 15, stiles 23 and 24, and rails 25, 26, and 27, define openings 28 and 29. The adjacent rails 19 and 25 of the top and bottom sashes may be complementally off-set, substantially as best shown in Figure 2, to provide an effective seal against cold air and dirt from the exterior. Suitable catches 30 are provided on the inner face of frame 10 for retaining the sashes in closed position.

The inner opening edges of the stiles and rails

2

may be slotted as indicated by the numerals 31, 32, 33 and 34 for slidably removably receiving closure panels comprising either a glass pane 35 or a screen 35a, the guide slots in the stiles 16 and 23, at the free side of the auxiliary window being extended through said stiles to facilitate insertion and removal of the panes or screens while the sash or sashes are in outwardly swung position (see Figure 4). These guide slots may be wide enough to receive either one or two closure panels in superposed relation, and in either case spring clips 36 secured to the stiles may have arms 36a suitably shaped to extend inwardly of the slots, with a minimum portion of the clips 10 exposed in the closure openings, yieldingly to urge the closure panel or panels toward one side relatively of the plane thereof, against the inner portions of the slots. The clips 36 retain the closure panels against rattling.

Guide strips 37, 37 may be secured to extend in parallelism along the top and bottom edges of each closure opening, these strips having oppositely turned flanges 37a for retaining either glass panes 35 or screens 35a against the outer face of the auxiliary window. The guide strips 37 are open at the end adjacent the free side of the window to permit insertion or removal of the panes or screens while the window is in open position.

In the use of the auxiliary window in the winter season, for example, it is normally maintained in the closed position, best shown in Figures 1, 2 and 4, with a single glass pane 35 retained in each closure opening 21, 22, 28 and 29, for effective insulation against cold air, and with a screen 35a retained over the top and bottom openings 21 and 28 by guide strips 37. Screens may be retained over the other two openings if desired. Should fresh air be required at any time, either the lower sash 15 may be left partly open, in the relative position shown in Figure 4, or the top or bottom panes 35, or both of the same, may be removed and inserted between the guide strips 37 of openings 22 and 28. If there are screens retained over the last-named openings the panes may be inserted in the slots 32 in superposed relation to the panes already received therein, in the manner previously described. During the warmer seasons of the year the auxiliary window may be normally maintained with the openings screened as described above for ventilating purposes. It is possible, however, with equipment as shown, to have as many as three closure openings open except for screens, as by storing two glass panes in the slotted portions of one of the openings and storing a third pane between the guide strips 37 of the same opening. Thus various combinations of glass or screen covered openings may be accomplished without the usual prob-

lem of what to do with closure panes or screens not necessarily required at a particular time.

In Figure 6 is shown a modified form of the invention, in which spaced slotted portions 40 and 41 are provided, in place of the above described single-slotted portions, for receiving glass panes or screens in various combinations, the operation and use thereof being otherwise similar.

Modifications of the invention may be resorted to without departing from the spirit thereof or the scope of the appended claims.

What is claimed is:

1. The combination with a window frame having an inwardly presented blind seat, of an auxiliary window received in said blind seat and hinged at one side to said window frame, said window having stiles and vertically spaced rails, said stiles and said rails being slotted around the inner edges thereof for receiving a closure panel in closed position thereof, the slot of the stile at the free side of the window being extended through the stile, a closure panel received in said slots and being insertable and removable through said extended slot at said free side of the window, and yielding means in said auxiliary window for yieldingly engaging said closure panel at one side relatively of the plane thereof to urge the same toward the opposite side of the slots therefor, said pressure members including guide portions being in the path of and thereby yieldingly engageable with the leading edge of said closure panel as the same is inserted through said extended slot and moved toward said closed position within said inner edge slots.

2. The combination with a window frame having an inwardly presented blind seat, of an auxiliary window received in said blind seat and hinged at one side to said window frame, said window having stiles and vertically spaced rails to provide a plurality of window openings, said stiles and said rails being slotted around the inner edges thereof in said openings for receiving closure panels in closed positions thereof, the slots of the stile at the free side of the window being extended through the stile, closure panels received in said slots and being insertable and removable through said extended slots at said free side of the window and a plurality of resilient pressure members in said auxiliary window in cooperation with each window opening thereof for yieldingly engaging said closure panel at one side relatively of the plane thereof to urge the same toward the opposite side of the slots of the respective window opening, said pressure members of the respective window openings including guide portions adapted to be in the path of and thereby yieldingly engageable by the leading edge of the closure panel as the same is inserted through said extended slot.

3. The combination with a window frame having an inwardly presented blind seat, of a window received in said blind seat and hinged at one side to said window frame, said window having stiles and vertically spaced rails, said stiles and said rails being slotted around the inner edges thereof for receiving a closure panel for a closed position thereof, the slot of the stile at the free side of the window being extended through the stile, and a closure panel received in said slots and being insertable and removable through said extended slot at said free side of the window, said slots having a width adapted to receive two closure panels in superposed relation, and yielding means being provided yieldingly to engage a panel at one side relatively of the

plane thereof when either one or two panels are received in the slots to urge the same toward the opposite side of the slots, said yielding means including guide portions being in the path of and thereby yieldingly engageable with the leading edge of said closure panel as the same is inserted through said extended slot and moved toward said closed position within said inner edge slots.

4. The combination with a window frame having an inwardly presented blind seat, of a window received in said blind seat and hinged at one side to said window frame, said window having stiles and vertically spaced rails providing a plurality of vertically spaced openings, said stiles and rails having guide slots around the inner edges thereof in said openings for receiving closure panels therein, the guide slots of the stile at the free side of the window being extended through the stile, closure panels removably and interchangeably receivable in said guide slots through said extended slots, parallel guide strips secured to said window adjacent the top and bottom edges of said vertically spaced openings, said guide strips being open ended at least at the free side of said window, and closure panels slidably receivable between said parallel guide strips from the open ends thereof and being interchangeable with the closure panels receivable in said guide slots.

5. The combination with a window frame having an inwardly presented blind seat, at a window received in said blind seat and hinged at one side to said window frame, said window having stiles and vertically spaced rails providing a plurality of vertically spaced openings, said stiles and rails having guide slots around the inner edges thereof in said openings for receiving closure panels therein, the guide slots of the stile at the free side of the window being extended through the stile, closure panels removably and interchangeably receivable in said guide slots through said extended slots, parallel guide strips secured to said window adjacent the top and bottom edges of said vertically spaced openings, and closure panels slidably receivable between said parallel guide strips and being interchangeable with the closure panels receivable in said guide slots, said guide slots being of width adapted to receive two closure panels in superposed relation, and yielding means being provided yieldingly to engage a panel relatively of the plane thereof when either one or two panels are received in the guide slots to urge the same toward the opposite side of the guide slots, said yielding means including guide portions being in the path of and thereby yieldingly engageable with the leading edge of said closure panel as the same is inserted through said extended slot and moved toward said closed position within said inner edge slots.
